H. J. FORSTER.
DRILL EXTENSION DEVICE,
APPLICATION FILED SEPT. 8, 1913.

1,104,110.

Patented July 21, 1914.

UNITED STATES PATENT OFFICE.

HARRY J. FORSTER, OF CHICAGO, ILLINOIS.

DRILL-EXTENSION DEVICE.

1,104,110.

Specification of Letters Patent.

Patented July 21, 1914.

Application filed September 8, 1913. Serial No. 788,666.

To all whom it may concern:

Be it known that I, HARRY J. FORSTER, a citizen of the United States, and a resident of Chicago, in the county of Cook and State of Illinois, have invented certain new and useful Improvements in Drill-Extension Devices, of which the following is a specification.

This invention relates to a device designed 10 to be used with drill extension telescoping tubes now known and used in the art in boilers and other like places, for drilling holes to which access by other means, is difficult.

15 One object of this invention is to obtain a device which may be readily attached to and detached from one of said tubes.

A further object is to obtain a device to 20 which a ratchet drill, or a part thereof, may be applied.

A further object is to obtain a device which, when attached to a drill extension tube, may be used to hold an end piece, a 25 drill, or other cylindrical device or tool.

25 A further object is to obtain a device which can be used for the purposes above named and which will be durable, not liable to get out of order, or break, and the application and working whereof will be readily understood by drill operators.

In drilling holes underneath boilers and other devices, it is at times convenient to have the drill ratchet interposed between the extension tubes and the drill, and at 35 other times it is convenient to have the extension tubes interposed between the drill ratchet and the drill, and the primary object of this invention is to obtain a device which is adapted to permit either of said 40 arrangements of the drill and extension tubes.

In the drawing accompanying and forming a part of this specification Figure 1 is 45 viewed as indicated by line 1, Fig. 2. Fig. 2 is an elevation of a modification of the construction illustrated in Fig. 1, at an angle of ninety degrees from said Fig. 1. Fig. 3 is a top plan view of the upper end 50 of the shell which is illustrated in Fig. 2, showing said modification. Fig. 4 is an elevation of the upper end of the shell which is illustrated in Figs. 2 and 3, viewed at an

angle of ninety degrees from said Fig. 2. And Fig. 5 is a vertical section of the lower 55 end of the shell illustrated in Fig. 1, showing a modification of said lower end.

A reference character applied to designate a given part indicates said part throughout the several figures of the drawing wherever the same appears.

A is a cylindrical shell, provided with a passage way of more than one diameter therethrough. Parts a of said passage way are of the same diameter, being substantially the same diameter as the outside diameter of the feed sleeve of a drill ratchet; part a^1 is of less diameter than part a ; and part a^2 is of substantially the same diameter as the larger one of 70 the several telescope tubes which form the ratchet extension used with this device. The diameter of part a^1 is substantially the same as the diameter of the feed screw of a 75 drill ratchet.

B is a slot in the upper end of shell A, and C is a bolt hole at right angles to slot B. Bolt hole C is screw threaded at C¹. Dotted (or broken) lines D, (Fig. 1), indicate the head of a bolt which can be inserted in 80 hole C, to extend through corresponding holes in the tube, or tubes, (X, Z, Fig. 1), on which said shell is to be secured. The shell is clamped to said tube, or tubes, by turning said bolt (D), so that the screw 85 threads thereon engage with the screw threads C¹. Bolt D has two functions, 1, to prevent tubes X and Z from turning, and 2, to clamp shell A closely to said tubes. The holes referred to in tubes X, Z, are lettered 90 Z¹, in Fig. 1.

The drill rods, as they are termed in the art, to which this device is attachable, often consist of telescoping tubes, so that said drill rods may be lengthened, when required. 95 In Fig. 1, X and Z illustrate one end of a drill rod made of telescoping tubes, and said tubes are shown as telescoped.

In the modification of above described construction of shell A, (illustrated in Figs. 100 3 and 4), the hole C is not provided with screw threads at either end, and a pin, D¹, is substituted for bolt D; lugs or ears E are provided on the shell A, and bolt D² is inserted in holes in said ears. The hole in one 105 of said ears is screw threaded (see d¹, Fig.

4) with threads corresponding with those on said bolt D^2 . The combined function of pin D^1 and pin or bolt D^2 , is the same as the function of bolt D; that is, D^1 prevents 5 turning or longitudinal movement of a tube having its end inserted in the shell, D^2 clamps said shell closely to said tube. In this construction the pin D^1 is provided with a groove F, in which groove pin or bolt f 10 is yieldingly held by the spring G. g is an abutment on the shell A provided with a hole therethrough in which the pin or bolt f is longitudinally movable. Pin or bolt f is provided with the head f^1 by means of 15 which it is retracted when it is desired to draw pin D^1 out. In this modification the pin D^1 is inserted before the bolt D^2 is tightened to clamp the shell A to the tube or other device which is inserted therein. Bolt 20 D and pin D^1 , respectively, are used to make it certain that the rotation of the tube in the shell A and of said shell will be in unison, that is, without slipping.

By detaching the upper end of shell A 25 from the remainder thereof I find said upper end, in either of the constructions shown, may be used to secure telescoping tubes firmly together, provided, of course, both said tubes have holes which are in alignment 30 so that the bolt D or pin D^1 may be inserted therethrough. Two of said tubes are indicated in Fig. 1 by lines X and Z, while a single tube is illustrated in Fig. 2 by full and broken lines X. The lower end of shell 35 A is provided with the abutments or ears H, one of which is on one side of slot I and the other of which is on the other side of said slot. One of the abutments or ears H is provided with a screw threaded hole and the other with a hole, through which holes the bolt J is extended with the screw threads on the bolt and in said hole in engagement. (See j , Fig. 1.)

j^1 are handles which extend through bolts 45 D^2 and J, respectively, by means of which said bolts are turned to clamp shell A to the cylindrical device on which said shell is placed.

In Fig. 5 W is a screw threaded shaft corresponding with the ordinary screw threaded shaft of a ratchet drill and K a sleeve in screw threaded connection with said shaft W. W^2 is a pin to rigidly secure shaft W to the shell A, to turn therewith. L is the 50 end of the ratchet drill which is obtained by shaft W and sleeve K, in combination with ratchet wheel M and handle N. A screw threaded sleeve corresponding with sleeve K is in ordinary use in drill ratchets, and the 55 ordinary feed sleeve of said ratchets is secured to the screw threaded feed shaft thereof by a pin in substantially the same manner in which pin W^2 secures shaft W to shell A.

W^1 , (Fig. 1), are lines which indicate a 65 button inserted in passage way a^1 , to close said passage way, and to form an abutment against which the center bearing of a ratchet drill will be forced in the operation of the device. Where the end of tube X is closed 70 the button W^1 is not required as said center bearing abuts against said closed end of tube X.

It will be observed that the annular rib forming the cylindrical wall of part a^1 of 75 the passage way through shell A, presents on the faces thereof abutments, or annular tables against which the ends of the tubes X and Z, and the flange on button W^1 abut, and by means of which the further movement of said parts in said passage way is prevented.

I claim:—

1. A shell provided with a cylindrical passage way of more than one diameter extending 85 longitudinally therethrough the part of said passage way which is of smallest diameter obtained by means of an annular rib with 90 tables on the faces thereof adapted to form abutments, and said shell also provided with longitudinally extending slots open at the 95 ends of said shell, lugs on said shell, adjacent to said slots, said shell and lugs provided with laterally extending holes and laterally extending screw threaded holes, in combination with screw threaded bolts to fit 100 said holes and the screw threads thereon to engage with the threads in the screw threaded holes, said holes and bolts therein arranged to contract the slotted portion of 105 said shell on to a cylindrical article contained therein at each end thereof.

2. A shell provided with a cylindrical passage way of more than one diameter extending 110 longitudinally therethrough the part of said passage way which is of smallest diameter being obtained by means of an annular rib with tables on the faces thereof adapted to form abutments, and said shell also provided with longitudinally extending slots 115 open at the ends of said shell, adjacent to said slots, lugs on said shell, said shell and said lugs respectively provided with laterally extending holes, in combination with a bolt provided with an annular groove, said 120 bolt adapted to extend through said laterally extending holes, means to contract the slotted portions of said shell on to the bodies contained in said cylindrical passage way, an abutment on said shell, a longitudinally 125 movable pin in said abutment, and means to yieldingly hold said pin in an advanced position to engage with said groove in the bolt which is in the laterally extending holes and adjacent to said pin.

3. A device comprising a shell provided with means to contract said shell on to bodies contained therein, and provided with

holes extending through the wall of said shell, the combination of a pin or bolt adapted to extend through said holes in said wall, and said pin or bolt provided with an annular groove adjacent to one end thereof, with an abutment on said shell, a longitudinally movable body in said abutment, and

means to yieldingly hold said last named body in an advanced position with the end thereof in said annular groove.

HARRY J. FORSTER.
